UNITED STATES PATENT OFFICE

2,491,394

COMBINED SLEEPING BAG AND CARRIER
FOR INFANTS

Bertha C. Rose, Boston, Mass., assignor to Rose-Derry Company, Newton, Mass., a corporation of Massachusetts

Application December 4, 1943, Serial No. 512,893

6 Claims. (Cl. 5—343)

1

This invention relates to improvements in a combined sleeping bag and carrier for infants.

It is an object of the invention to provide, in a unitary construction, an article which may be efficiently and safely used to carry or transport an infant such as from the hospital to the home and between the crib and the carriage, which may also be used to hold the baby during feeding, and which may serve as a sleeping bag for the baby in the crib or carriage.

It is further an object of the invention to provide an article which may be used for the purposes described which is simple in design, attractive in appearance, readily cleanable, and into which the baby may be easily inserted and safely held without requiring any complicated folding operations or fastening means.

Essentially the article comprises a relatively small-sized pad or mattress adapted to be laid flat on any surface or to be readily carried and transported, the pad having a removable covering and a supplemental layer or cover section permanently attached to the pad covering to provide a pocket or bag portion closed at the bottom and sides and adapted to receive the infant.

In one form of the article, provision is made for taking care of the increasing length of the baby during the first year of its life by providing supplemental means to decrease or increase the depth of the pocket as desired.

Further objects and advantages of the improvements will be more readily apparent from the following description of preferred embodiments thereof as disclosed in the attached drawings, in which

Fig. 1 is a plan view of the article, a portion of the cover section being broken away for clearness in illustration;

Fig. 2 is a bottom view of the article, a portion of the pad covering being broken away for clearness in illustration;

Fig. 3 is a side elevation of the article showing the manner of opening the flap of the pocket to more readily receive the infant;

Fig. 4 is a longitudinal section taken through the article of Fig. 1;

Fig. 5 is a side elevation of a modified construction in which the pocket is made adjustable, the slide fastener closure on the side being partially opened;

Fig. 6 is a longitudinal section of the article shown in Fig. 5, the pocket being shortened to take care of a small baby;

2

Fig. 7 is a longitudinal section similar to Fig. 6 showing the full length of the pocket used to receive a larger baby; and

Fig. 8 is a fragmentary detail view showing the manner of fastening the adjustable bottom piece in the pocket.

Referring to Fig. 4, there is indicated at 10 a pad or mattress which is inserted within a protective covering 12. The covering 12 includes the 10 overlapping portions 14 and 16 on the under side of the pad 10 providing an entrance opening in the bottom layer of the covering through which the pad may be inserted as shown in Fig. 2. Except for the opening between the flaps 14 and 16, the cover 12 completely encloses the pad or mattress. The top portion or layer of the covering 12 may consist of waterproof material or may have a waterproof coating thereon. The portion of the top covering 12 which is enclosed within the pocket, as indicated at 18, may be made separate from the head or pillow section 20, as indicated in Fig. 4. The portions 18 and 20 may be seamed together as at 22, while the section 20 is extended over the upper end of the pad 10 and seamed at 24 to the bottom layer of the covering 12.

The mattress covering 12 has attached thereto a supplemental cover section 26 to form the bag or pocket 28. The cover section 26 is unitarily attached to the pad cover 12 by the finished seam 30 at the bottom or foot end of the bag and along the opposite sides of the article. As shown, the cover section 26 is made of quilted, tufted, or similar material to provide warmth and to present an attractive appearance. The cover section 26 may be formed with a free flap 32 at the upper or head end whereby the entrance to the pocket may be opened up to more readily receive the infant, as shown in Fig. 3. The flap 32 may be tied down after the infant has been placed in the pocket by means of the tapes 34 attached to the corners of the flap 32 and to the seam 30. The tapes 34 may also be used to tie the article to the crib or carriage when the article is used therein.

It will be apparent that the article described may be readily used to carry the baby. While being used in this manner, the pad and the quilted cover section provide support for the infant and make it easy for a person to carry the baby while so supported. That is, the article as a carrier is more than merely a sack for carrying a baby. The article may also be used to lay the baby in a crib or carriage, and it is therefore a simple matter to transport the baby from the crib to

the carriage since the baby does not need to be removed from the pocket in which it is inserted.

Since babies in the early months have a rapid growth, it may be desirable to provide an article which may take care of the body for a longer period of time by providing means for adjusting the size of the pocket. Such a construction is disclosed in Figs. 5, 6, 7 and 8, in which the pad 40 may be made somewhat longer than the pad 10 of Figs. 1 to 4. The pad 40 is enclosed in a covering 42 and a quilted cover section 44 is attached to the pad covering 42 by the seam 46 as in the first embodiment. In this form a slide fastener closure 46' may be provided to attach one side margin of the cover section 44 to the pad covering 42. The depth of the pocket 48 between the cover section 44 and the pad covering 42 may be adjusted to provide a short pocket as in Fig. 6, or a longer pocket as in Fig. 7. There is provided a fabric panel 50, one end of which is attached as at 52 to the top portion of the pad covering 42 at a point spaced from the bottom end thereof. The free end 54 of the panel 50 may be provided with snap fasteners 56 adapted to be fastened either to the fastening elements 58 or 60. The fastening elements 58 and 60 are spaced apart as illustrated, whereby the fastening elements 56 and 58 may be secured together as in Fig. 6 to bring the fold of the panel 50 adjacent the attachment 52 and to shorten the pocket 48 in Fig. 6, or the fastening elements 56 and 60 may be attached as in Fig. 7 to provide the full depth of the pocket.

Various other changes and modifications may be made in the commercial design of the article without departing from the spirit of the invention as expressed in the appended claims.

I claim:

1. An infant's sleeping bag or carrier comprising a mattress pad, a fabric covering having top and bottom layers and completely enclosing the pad, the bottom layer of said covering having a transverse opening, intermediate its ends, for the insertion and removal of said pad, the top layer of said fabric covering having a waterproof coating thereon, a supplementary fabric piece attached to the fabric covering of the pad at the foot end and sides of the bag and forming a pocket opening toward the head end of the bag to receive the infant, said fabric piece being composed of quilted material, the mattress pad being thicker than the quilted fabric piece to afford support for carrying the infant, the end of said fabric piece at the mouth of said pocket being free from attachment to the pad covering at the sides thereof to form a flap which may be folded back to enlarge the opening to the pocket, and tape means for tying down the flap after the infant has been inserted in the pocket.

2. In an infant's sleeping bag, a double layer of material, joined together at one end and the sides thereof to form a pocket, the closed end of said pocket forming the foot end of said sleeping bag, the said pocket being open at the head end to receive the infant, and means for adjusting the depth of the pocket comprising a fabric strip secured at one end to an inside wall of the pocket, and means for securing the other end of said fabric strip to the other inside wall of the pocket at more than one point at different distances from the bottom of the pocket to vary the effective depth of the pocket.

3. In an infant's sleeping bag comprising a mattress pad, a fabric covering having top and

bottom layers completely enclosing said pad, a piece of quilted material joined to the marginal edges of said top layer at one end and the sides thereof to form a pocket, the closed end of said pocket forming the foot end of said sleeping bag, the said pocket being open at the head end to receive the infant, a fabric strip having a width substantially as wide as the pocket secured at one end to said top layer at a line spaced from the foot end of the bag, and detachable means for attaching the other end of said strip to the underside of said quilted material within said pocket to form a loop of said strip across the bottom of said pocket, said loop terminating at a distance from the foot end of the sleeping bag to shorten the effective depth of said pocket, whereby said fabric strip may be detached at one end in order to use the full depth of the pocket.

20 4. An infant's sleeping bag and carrier, comprising a mattress pad, a fabric covering having top and bottom layers completely enclosing the pad, a supplementary piece of quilted fabric joined to said top covering layer at one end and the sides thereof to form a pocket, the closed end of said pocket forming the foot end of said sleeping bag, the said pocket being open at the head end to receive the infant, at least one side margin of said quilted fabric being joined to said pad covering by a slide fastener, a fabric strip disposed within the pocket and having a width substantially as great as the quilted fabric, means for attaching one end of said fabric strip to an inside wall of said pocket, and means for detachably connecting the opposite end of said fabric strip to the other inside wall of said pocket to form a loop, whereby the effective depth of said pocket may be shortened.

25 5. An infant's sleeping bag and carrier comprising a mattress pad, a fabric covering having top and bottom layers completely enclosing the pad, a supplementary fabric section joined to the top covering layer at one end and the sides thereof to form a pocket, the closed end of said pocket forming the foot end of said sleeping bag, the said pocket being open at the head end to receive the infant, at least one side margin of said supplementary fabric section being joined to said pad covering by readily separable fastening means whereby the pocket may be opened from the side, a fabric strip disposed within the pocket, the width of said fabric strip being sufficient to extend from side to side of said pocket, and means fastening the ends of said fabric strip 30 to opposed inside walls of said pocket to form a loop across said pocket to shorten the effective depth of said pocket.

35 6. An infant's sleeping bag or carrier comprising a mattress pad, a fabric covering having top and bottom layers enclosing the pad, said covering having a transverse opening for the insertion and removal of said pad, a supplementary fabric piece attached to the fabric covering of the pad at the foot end and sides of the bag and forming a pocket opening toward the head end of the bag to receive the infant, said fabric piece being composed of quilted material, the mattress pad being thicker than the quilted 40 fabric piece to afford support for carrying the infant, the end of said fabric piece at the mouth of said pocket being free from attachment to the pad covering at the sides thereof to form a flap which may be folded back to enlarge the opening to the pocket, and tape means for tying 45

down the flap after the infant has been inserted in the pocket.
